H. HASTINGS,
FLUID GAGE,
APPLICATION FILED APR. 9, 1919.

1,379,404.

Patented May 24, 1921.

UNITED STATES PATENT OFFICE.

HERBERT HASTINGS, OF BRIGHTON, NEW YORK.

FLUID-GAGE.

1,379,404.

Specification of Letters Patent. Patented May 24, 1921.

Application filed April 9, 1919. Serial No. 288,839.

To all whom it may concern:

Be it known that I, HERBERT HASTINGS, a citizen of the United States, and resident of Brighton, in the county of Monroe and State of New York, have invented new and useful Improvements in Fluid-Gages.

This invention relates particularly to fluid gages such as may be used for indicating the amount of fluid in the fuel tanks for 10 automotive motors or similar applications and has as its objects to provide—

An improved method of supporting the float mechanism in a tank flange or adapting cylinder.

15 An improved float and guide plate construction.

Other objects and features of my invention will be set forth in connection with the following description of the embodiment of 20 the invention as illustrated in the accompanying drawings, in which—

Figure 1 is a partial plan view of the head of a gage embodying my invention.

Fig. 2 is a partial sectional view in elevation taken on the line X' X' of Fig. 1.

25 Fig. 3 is a broken plan view of the flange or adapting cylinder shown in Fig. 2.

Fig. 4 is a sectional view, taken on the line X³ X³ of Fig. 3.

30 Fig. 5 is a plan view of the plate 2 shown in Fig. 2.

Fig. 6 is a sectional view taken on the line X⁵ X⁵ of Fig. 5.

35 Fig. 7 is a sectional view showing the plate—assembled in the flange—taken on the line Y³ Y³ of Fig. 3, and on the line Y⁵ Y⁵ of the plate Fig. 5.

Fig. 8 is a plan view of the dial shown in Fig. 2.

40 Fig. 9 is a sectional view in elevation showing the dial and plate assembled, taken on the line X⁸ X⁸ of Fig. 8, and the line X⁵ X⁵ of Fig. 5.

Fig. 10 is an elevation view, looking to 45 the left, of the float unit shown in Fig. 2.

Fig. 11 is a plan view of the float unit shown in Fig. 10.

Like characters of reference refer to like parts throughout the several views of the 50 drawings.

1 is the adapting cylinder the lower end of which is flared outwardly for soldering to a tank and the upper end is flanged inwardly at 1^a; this flange, is pierced with a 55 central opening 1^b, and is provided with depressed seats or ears 1^c spaced around the central opening.

2 is a plate, to the underside of which is attached the float mechanism, and has extending raised projections 2^b and an extending depressed ear or projection 2^d; the projections 2^b are adapted to rest in the seats 1^c of the flange so that the top surface of the projections is flush with the top surface of the flange 1^a and the depressed projection 2^d is adapted to hook under a flat portion of the flange 1^a so that that side of the plate will not lift out of the flange. The sides of the raised projections are adapted to register with the sides of the depressed seats in 60 the flange, thereby maintaining the plate in a central position on the flange. The flat portion of the plate is pierced with two side holes 2^e and a central hole 2^f, and the raised projections are provided with notches 2^g. 75

3 is a graduated dial plate on which are inscribed the readings or calibrations of the gage. Spaced around the periphery of this plate are provided downwardly projecting ears 3^a adapted to index with the notches 80 2^g of the plate 2 and adapted to clench thereunder to attach the dial plate to the upper surface of the projections 2^b thereof in a predetermined and central position; the dial plate is pierced at 3^b in alignment with 85 the hole 2^f in the plate 2, see Fig. 8.

4 is a U shaped float guide and spiral support, the upper ends of which are reduced in diameter and shouldered at 4^a and which ends are adapted to enter the holes 2^e 90 shouldering against the underside thereof and riveted over on the upper side to accomplish a rigid connection of these two parts. The lower cross portion of the U is provided with a bottomed hole 4^b which 95 serves as a pivot bearing seat for the shaft 5.

The indicator shaft 5 is formed from square or flat stock, which is twisted to form a helix of a proper helical angle to cause it to rotate the desired amount as the float 100 slides up and down from top to bottom of the guide, and is provided at its lower end with a reduced pivot point 5^a adapted to bear in the pivot seat 4^b, and at its upper end with a reduced shouldered portion 5^b 105 adapted to pass through the hole 2^f of plate 2 and shoulder beneath the underside thereof in a manner free to rotate. The extreme upper end carries an indicating pointer 6 which is adapted to traverse the graduated 110 scale of the dial 3.

The float 7 is provided with a central clearance hole 7^a through which the indicator shaft passes, and with side slots or

notches 7^b providing clearances for the side rods of the support 4 and also providing seats for accommodating the float guide plate 8.

5 The float guide plate 8 which is approximately U shaped is adapted to wrap around the float centrally, with the cross member of the U lying in the bottom of one of the slots 7^b in the float, and the two sides of the 10 U lying across the upper and lower surfaces of the float central therewith. The upper member of the plate is forked at its end at 8^a to straddle one leg of the guide to prevent the float from turning on its axis, and 15 the tongue 8^b which is sheared out to form this fork, is bent downwardly to embrace the bottom of the second slot in the float and the extreme end of this tongue is pointed and bent inwardly penetrating the float to 20 provide anchorage. The lower member of the plate is formed into a second tongue 8^c which is bent upwardly embracing the bottom of the same slot and the extreme end of this tongue is also pointed and bent inwardly 25 penetrating the float to provide anchorage. It will thus be seen that the plate is held securely to the float in all directions. The upper member of the plate is pierced at 8^e centrally with the float, to conform with the 30 shape of the shaft 5 so that as this plate slides up and down in engagement with the helix the shaft is caused to rotate. The lower portion of the plate is pierced centrally at 8^d by a hole sufficiently large to 35 allow the outside corners to pass through and rotate therein.

The parts 2, 3, 4, 5, 6, 7 and 8 when assembled as above described constitute what I 40 will call the gage unit, see Fig. 2 and the parts 9, 10, 11 and 12 I will call the gage head, see same figure.

To assemble the complete gage, insert the lower portion of the gage unit down through the central opening 1^b of the adapting cylinder 1, bring the ears 2^b of the plate 45 into correct position for entering the seats 1^c , hook the ear 2^d under the flange 1^a and slip the plate into place with the ears 2^b resting in the depressions 1^e of the adapting 50 cylinder. This brings the under surface of the dial to rest on the upper surface of the flange 1^a . After assembling the parts 10, 55 11 and 12 in the cap 9 as shown in Fig. 2, screw the cap down over the outside of 1 until the parts are firmly compressed, the relatively soft yieldable gasket 10 compresses over the edge of the dial 3 forming a tight seal against the upper surface of the flange 1^a and the pressure of the gasket 10 on the 60 edge of the dial holds the dial securely on the top of the flange 1^a and the plate securely in the seats 1^c .

Having thus described my invention in

general what I claim as new and desire to secure by Letters Patent is—

65 1. In a fluid gage, a tubular casing with an inturned flat flange provided with depressions separated by undepressed portions, a plate provided with ears adapted to seat in said depressions, a float mechanism supported on one side of said plate, a dial attached to the other side of said plate resting on said flange outside of the depressions and means for maintaining the dial on the flange and the plate in the depressions. 75

2. In a fluid gage, a tubular casing with an inturned flat flange provided with depressions, separated by undepressed portions, a plate provided with ears adapted to seat in said depressions and with an ear adapted to 80 engage the under side of an undepressed part of the flange, a float mechanism supported on one side of the plate, a dial on the other side of the plate resting on said flange, means for maintaining the dial on the flange 85 and the plate in the depressions.

3. In a fluid gage, a plate provided with supporting ears, a U shaped float guide with its ends riveted to the plate, a helical indicator shaft with one end revolvably supported 90 in the plate and provided with an indicator, a float adapted to slide up and down the guide and provided with means for engaging the helix of the indicator shaft to cause it to revolve. 95

4. In a fluid gage; a graduated indicating plate provided with attaching ears, a float mechanism attached thereto including a supporting plate, an indicating pointer, a pointer shaft, and a guide; a float provided with a 100 guide plate adapted to rotate the pointer shaft and to engage the guide to keep the float from rotating.

5. In a fluid gage; a graduated dial, a float action mechanism attached thereto including an indicating pointer, a pointer shaft, and a guide; a float, a float plate embracing the top, bottom and sides of the float and provided with barbs for securing it thereto and also provided with means for 105 revolving the pointer shaft and for engaging the guide. 110

6. In a fluid gage, a graduated dial, a float action mechanism attached thereto including an indicating pointer, a pointer shaft, and a 115 guide; a float provided with side grooves, a float plate embracing the top, bottom and side grooves of the float and provided with barbs for securing it to the float and also provided with means for revalving the 120 pointer shaft and for engaging the guide.

HERBERT HASTINGS.
